INVENTOR.

George H. Tansley

BY *S. Jay Teller*

ATTORNEY.

UNITED STATES PATENT OFFICE.

GEORGE H. TANSLEY, OF HARTFORD, CONNECTICUT, ASSIGNOR TO COLT'S PATENT FIRE ARMS MANUFACTURING COMPANY, OF HARTFORD, CONNECTICUT, A CORPORATION OF CONNECTICUT.

MAGAZINE SAFETY DEVICE FOR AUTOMATIC PISTOLS.

Application filed August 5, 1926. Serial No. 127,429.

The invention relates particularly to a safety device of the type which renders the firing mechanism of the pistol inoperative when the magazine is withdrawn or partly withdrawn from its normal position. It is well known that the user of an automatic pistol frequently assumes that the withdrawal of the magazine necessarily leaves the pistol in inoperative condition and that the trigger may then be safely pulled without danger of discharge. As a matter of fact, however, one cartridge may remain in the firing chamber even after the magazine is withdrawn and this common erroneous assumption on the part of the users constitutes a serious source of danger in connection with automatic pistols.

Many different devices and mechanisms have been proposed and used for eliminating this source of danger, these prior devices and mechanisms making use of a number of different principles, some of them locking certain parts of the firing mechanism and others breaking the train of connection between the trigger and other parts of the firing mechanism. By the present invention I have provided a safety device of the class described which involves breaking the connection between the trigger and the sear when the magazine is withdrawn, and with the result that the sear is not moved when the trigger is pulled.

The object of the invention is to provide a safety device of the class described which is very simple in construction and reliable in operation, which will operate satisfactorily notwithstanding minor variations in the size and shape of the magazine, and which may be readily combined with other safety features. Further objects of the invention will be apparent from the following specification and claims.

In the accompanying drawing, I have shown the embodiment of the invention which is now deemed preferable, but it will be understood that variations in construction may be made within the scope of the appended claims without departing from the spirit of the invention.

Of the drawing,

Fig. 1 is a plan view of an automatic pistol embodying the invention.

Fig. 2 is a fragmentary combined side and longitudinal sectional view of the pistol, the hammer being shown in cocked position and the magazine being shown in its normal position.

Fig. 3 is a view similar to Fig. 2 except that it shows the magazine partly withdrawn.

Fig. 4 is a fragmentary side view with the parts in the same position as in Fig. 2.

Figs. 5, 6 and 7 are perspective views showing the trigger bar, the sear and the actuating slide respectively.

The pistol shown in the drawing is similar to that shown in the Browning Patent, No. 1,276,716, dated August 27, 1918, and reference is made to that patent for a full disclosure of the details of construction.

The pistol comprises a frame 1, having a magazine chamber 2 in the grip portion thereof, a barrel 3, a breech block 4 longitudinally movable on the frame 1, a hammer 5 adapted to engage a firing pin 6, a sear 7 adapted to hold the hammer in cocked position, and a trigger 8 connected with a trigger bar 9 for moving the sear to release the hammer. A magazine 10 of any usual or preferred form is normally located in the chamber 2, being held in place by a manually releasable latch 11. By releasing the latch the magazine can be removed for reloading.

The sear 7 is pivotally mounted in the frame by means of a pivot pin 12. The trigger bar 9 is located in a recess at the left side of the frame and is pivoted at its forward end to the upper portion of the trigger 8. A spring 13 tends to move the trigger bar 9 upward about its forward pivotal connection. The trigger bar 9 carries at its rear end a transversely extending lug 14 and, with the trigger bar in its uppermost position, this lug is so located that it will engage the sear when the trigger is pulled and the trigger is moved forward. However, if the trigger bar 9 is moved down-

ward in opposition to the spring 13 the lug 14 will be brought opposite a notch 15 in the sear, with the result that the sear is not moved when the trigger is pulled.

5 As shown in Fig. 4 the breech block 4 is provided with a recess 16 into which an enlargement 17 on the trigger bar may project when the said breech block slide is in its forward normal or firing position. It will 10 be obvious that when the breech block 4 is in any position except its normal firing position as shown in Figs. 2 and 4, the trigger bar will be forced downward so that the projection 14 will be opposite the notch 15 15 in the sear. In this way the pistol is rendered inoperative except when the breech block is in its normal position.

In accordance with the invention I make use of the vertically movable trigger bar 20 for also rendering the firing mechanism inoperative when the magazine is withdrawn or partly withdrawn. To this end I provide a longitudinally movable slide 18 which is suitably guided in the frame. As 25 shown the slide has two main portions 18^a and 18^b which are offset from each other, the portion 18^a fitting a central slot in the upper part of the frame and the portion 18^b being located at the side of the chamber 30 in the frame which contains the hammer. A spring is provided for pressing the slide in the forward direction and as shown there is a coil spring 19 located in a groove at the side of the portion 18^b and abutting against 35 a pin 20 carried by the side wall of the frame. A transverse pin 21 carried by the frame extends through a slot 22 in the portion 18^a of the slide and serves to limit the sliding movement.

40 The forward end of the slide 18 is normally engaged by the magazine 10 when the magazine is in its normal position as shown in Fig. 3. When so engaged by the magazine the slide is held in its rearward position in opposition to the action of the spring 19. When the slide is withdrawn, or partly withdrawn, the slide is pushed forward by the spring into the position shown 45 in Fig. 3. It will be observed that the forward end 18^a of the slide 18 is bevelled at 18^c so that the slide is easily forced backward when the magazine is again inserted.

The slide 18 is formed with a cam surface at 23 which is positioned to engage the projection 14 of the trigger bar when the slide is moved forward by the spring 19 as already described. The cam surface 23 moves the trigger bar downward so that the projection 14 registers with the notch 15 in the sear, and in this way the firing mechanism is rendered inoperative.

From the foregoing description it will be observed that whenever the magazine is withdrawn or partly withdrawn, the slide 18 will be moved by the spring 19 to the

position shown in Fig. 3, thus moving the trigger bar downward to its inoperative position. With the trigger bar in this position the trigger may be pulled without moving the sear and it is thus impossible to 70 fire the pistol. It will also be observed that the slide 18 does not in any way interfere with the movement of the trigger bar downward to its inoperative position by means of the breech block 4. The slide 18 engages 75 the rear surface of the magazine with the result that the slide is held in its proper position by the magazine notwithstanding any minor defects or variations in the length of the magazine or in the shape of 80 the upper rear corner thereof.

What I claim is:

1. In an automatic pistol having a frame provided with a magazine chamber in the grip portion thereof, a removable magazine in the chamber, a breech block longitudinally movable on the frame, a pivoted hammer, a sear, a trigger, and a trigger bar located at one side of the frame and provided at the rear end with a transverse inward extending projection adapted to engage the sear, the rear end of the said trigger bar with the projection being normally held in an upper operative position in which the projection is adapted to engage the sear and being movable by the slide to a lower inoperative position in which the projection cannot engage the sear, the combination with the aforesaid parts of a longitudinally movable actuating slide located in a recess in the top of the frame and adjacent the rear of the magazine chamber and normally held in a rearward position by reason of engagement with the magazine, a spring for moving the said slide forward so as to project into the magazine chamber when the magazine is removed, and a cam surface on the actuating slide for engaging the rear end of the said bar to move it to the said inoperative position when the slide is moved forward by the spring. 100

2. In an automatic pistol having a frame provided with a magazine chamber in the grip portion thereof, a removable magazine in the chamber, a breech block longitudinally movable on the frame, a pivoted hammer at the rear of the magazine chamber, a sear, a trigger, and a trigger bar located at one side of the frame and provided at the rear end with a transverse inward extending projection adapted to engage the sear, the rear end of the said trigger bar with the projection being normally held in an upper operative position in which the projection is adapted to engage the sear and being movable by the slide to a lower inoperative position in which the projection cannot engage the sear, the combination with the aforesaid parts of a longitudinally 115 120 125 130

movable actuating slide located in part in a central recess in the top of the frame between the magazine chamber and the hammer and having an off-set portion at one side of the hammer and adjacent the trigger bar, the said slide being normally held in a rearward position by reason of engagement with the magazine, a spring for moving the said slide forward so as to project into the magazine chamber when the magazine is removed, and a cam surface on the off-set portion of the actuating slide for engaging the rear end of the said bar to move it to the said inoperative position when the slide is moved forward by the spring.

GEORGE H. TANSLEY.
